UNITED STATES PATENT OFFICE.

MANNA M. PRATT, OF GREEN CITY, MISSOURI.

WHEEL.

1,112,554.

Specification of Letters Patent.

Patented Oct. 6, 1914.

Application filed February 15, 1913. Serial No. 742,760.

To all whom it may concern:

Be it known that I, MANNA M. PRATT, citizen of the United States, residing at Green City, in the county of Sullivan and State of Missouri, have invented certain new and useful Improvements in Wheels, of which the following is a specification.

This invention relates to improvements in vehicle wheels, more particularly to wheels employed upon automobiles and like vehicles, and has for one of its objects to provide a wheel having a yieldable hub structure whereby a wheel is produced having all of the advantages of the ordinary pneumatic tire without danger of puncture or the disintegration of the tire.

Another object of the invention is to provide a simply constructed device whereby the parts are readily renewable without dissecing the remainder of the wheels.

With these and other objects in view, the invention consists in certain novel features of construction as hereafter shown and described and then specifically pointed out in the claim; and in the drawings illustrative of the preferred embodiment of the invention, Figure 1 is a side elevation of a wheel constructed in accordance with the invention; Fig. 2 is an enlarged view of the hub portion of the improved wheel with the outer disk or web removed, and with the parts represented as under strain. Fig. 3 is a section on the line 3—3 of Fig. 2.

Corresponding and like parts are referred to in the following description and indicated in all the views of the accompanying drawings by the same reference characters.

The improved wheel is adapted to be mounted upon an axle journal of ordinary construction and may be provided with a conventional ball bearing or not, as may be preferred. For the purpose of illustration the wheel is shown as supplied with a conventional ball bearing, and comprises a main hub member 10 mounted upon the axle journal represented at 11 with the anti-friction bearing balls 12, an adjustable stop collar 13 and binding nut 14, these parts being of the usual construction. Extending from the hub portion 10 is an integral disk or web 15 having an annular integral flange 16 near the body 10, the web 15 being located relatively near the inner end of the body of the hub.

Bearing around the outer portion of the hub body 10 is a sleeve 18 and extending

from this sleeve is a disk or web 19 similar to the web 15 and bearing against the outer edges of the flange 16. The webs 15—19 are coupled at suitable intervals by clamp 60 bolts 20. Disposed between the webs or disks 15—19 at their outer edges is an annular ring member 17 slidable between the members 15—19.

Directed inwardly from the annular member 17 are a plurality of projections or enlargements 21 uniformly spaced apart and corresponding in number to the spokes of the wheel. Each of the projections 21 and the portion of the annular member 17 adjoining thereto is provided with a socket indicated at 22 and preferably slightly tapered to receive the inner end of one of the spokes, the latter being represented at 23. The disk or web 15 is cut-away, as represented at 24, 70 between the projections 21, while the plate 19 is likewise cut-away, as represented at 25, opposite the cut-away portions 24, to lighten the disks or webs, the portions of the webs between the cut-away portions being extended outwardly to form guards or guides 26 to the annular member 17, as hereafter explained.

Pivoted at their inner ends at 28 in the flange 16 are a plurality of guide pins or 85 rods 29 which extend through apertures in the member 17 and project beyond the same, as shown. The rods 29 are thus slidable through the apertures in the member 17, and the apertures are rounded to permit a 90 slight rolling motion between the rods and the annular member as the hub and its attachments including the webs 15—19 and flange 16 are deflected under strain as illustrated in Fig. 2, and thus prevent cramping 95 of the parts.

The rods 29 are located midway between the spokes 23, and surrounding each rod between the flange 16 and the annular member 17 is a spring 30, preferably in coiled 100 form, and exerting its force to maintain the hub and its attachments normally in concentric relation to the annular member 17.

The rim or "felly" portion of the wheel is represented conventionally at 31 and receives the outer ends of the spokes 23, preferably in socket members 32. The rim 31 may be of any suitable form, but for the purpose of illustration, a conventional metal rim is shown provided with a yieldable tire 110 33 of rubber or like material, but it will be understood that it is not desired to limit

the invention to any specific form of rim or tire.

By this simple arrangement it will be obvious that with a wheel thus constructed and assembled, the springs 30 acting with equal force from all sides, maintain the annular member 17 in concentric relation to the axle journal 11 under a normal load, but when an abnormal load is applied to the vehicle the hub and its attachments will move downwardly, the rods 29 which, for the time being are located downwardly will move through the annular member 17 against the resistance of the springs 30, while the rods 15 which for the time being are directed upwardly, will likewise move downwardly but will not exert any force against the springs, while the remaining rods will oscillate on their pivots 28 and slide through the rounded apertures of the member 17 with a rolling movement and will thus be prevented from cramping. By this simple means, it will be obvious that a substantial, compact, and effectual spring hub is produced which 25 will yield under abnormal pressure and absorb all concussions which may be imparted to the rim and prevent them from being communicated to the running gear or the body of the vehicle. In event of the wheel 30 rim striking obstructions or sinking in cavities or depressions the same action will result, but in a reverse order, the springs absorbing the concussion and relieving the running gear from its effects.

35 The improved device is simple in construction, can be inexpensively manufactured and applied, and produces all of the beneficial effects of the pneumatic tire without danger of puncturing a tire.

40 The wheel may be constructed of any

weight and applied to vehicles of any form or weight or employed for any purpose, but as before stated, is more particularly applicable to automobile wheels and wheels employed in connection with motor vehicles. 45

The rods 29 are of sufficient length to prevent them from being pulled out of the apertures in the flange 17 when the hub and its attachments are depressed to their greatest extent. A dust cap 34 is located upon the hub, as shown.

Having thus described the invention, what is claimed is:

A wheel including a hub, an inner web integral with said hub, an annular bearing 55 flange integral with said web, a sleeve slideable on the hub, an outer web integral with said sleeve, said outer web bearing against the extremity of the flange and being spaced thereby from the inner web, a cap carried 60 by the hub and bearing against the sleeve to hold the web formed integral with said sleeve in engagement with the flange, means for connecting said webs together, an annular member slidably mounted between said 65 webs externally of the supporting flange, a plurality of radially disposed rods extending through the supporting flange and pivotally connected thereto, said rods being slidable through the annular member, yieldable members interposed between the supporting flange and the annular member, a wheel rim, and a plurality of spokes connecting said rim and annular member. 70

In testimony whereof I affix my signature 75 in presence of two witnesses:

MANNA M. PRATT. [L. S.]
